UNITED STATES PATENT OFFICE

144,755

DESIGN FOR A CLOTH DISPLAY RACK

Edmond P. Bixer, New York, N. Y.

Application March 12, 1945, Serial No. 118,447

Term of patent 14 years

(Cl. D80—9)

To all whom it may concern:

Be it known that I, Edmond P. Bixer, a citizen of the United States of America, residing at New York, in the county of New York and State of New York, have invented a new, original, and ornamental Design for a Cloth Display Rack, of which the following is a specification, reference being had to the accompanying drawings, constituting a part hereof:

I claim:

The ornamental design for a cloth display rack, as shown.

EDMOND P. BIXER.
